(57) CLAIM

The design for a sportsman's potty, as shown and described.

DESCRIPTION

FIG. 1 is a front, side and top perspective view of a sportsman's potty showing my new design;

FIG. 2 is a front elevation view thereof;

FIG. 3 is a rear elevation view thereof;

FIG. 4 is a side elevation view, it being understood the opposite side is a mirror image thereof; and,

FIG. 5 is a bottom plan view thereof.
